INVENTOR
EDWARD NUEBLING
BY
ATTORNEY

UNITED STATES PATENT OFFICE.

EDWARD NUEBLING, OF NEW YORK, N. Y.

WINDOW SCREEN.

Application filed December 12, 1923. Serial No. 630,073.

To all whom it may concern:

Be it known that I, EDWARD NUEBLING, a citizen of the United States, and a resident of the borough of Manhattan, in the city, county, and State of New York, have invented certain new and useful Improvements in Window Screens, of which the following is a specification.

This invention relates to window screens and has for its principal object to provide a new and improved construction of an extensible window screen, the sections of which are pivotally mounted to an extensible supporting frame so as to permit the screen to be opened without necessitating the removal thereof from the window frame.

Another object is to provide means for locking the pivotally mounted sections of the screen in operative position. A further object is to so construct the window screen and frame therefor that the window opening will be free and unobstructed when the sections of the screen are swung upon their pivots to opened position.

Another object is to provide the outer supporting frame with means for quickly and easily securing or removing screen to the window frame.

For the accomplishment of these and such further objects as will be apparent to those skilled in the art to which this appertains the invention consists in the construction, combination, and arrangement of parts, as hereinafter more fully described and as illustrated in the accompanying drawings forming a part hereof, and in which the examples are shown as illustrating but not as limiting the principles of my invention.

Referring to the drawings Fig. 1 is a front elevation of my improved window screen in partly extended operative position.

Fig. 2 is a top view of the structure shown in Fig. 1.

Figs. 3, 4 and 5 are sections on the lines 3—3, 4—4 and 5—5 respectively of Fig. 1.

Fig. 6 is a view similar of Fig. 1 of a modified form of construction.

Fig. 7 is a top view of the structure shown in Fig. 6.

Fig. 8 is a detail top view showing a modified construction for permanently securing the screen to the window frame, and Fig. 9 is a sectional detail.

As shown in Figs. 1 to 4 of the drawings an outer supporting frame is composed of a pair of extensible sections, each consisting

of a vertical upright 11 having a horizontal cross bar 12 secured to the lower end thereof. One of the cross bars 12 is provided with a dovetailed guideway 13 in which a tongue 14, projecting laterally from the other of said cross bars engages. A screen 15 formed by the extensible sliding sections 16 and 17 is pivotally secured, adjacent to its corners, to the supporting frame by the following means.

The junctions of the cross bars 12 with the uprights 11 are reinforced by the corner plates 18 each of which has a horizontally extending web 19 which is seated within a recess cut into the top face of the cross bar so as to bring the upper face of the web flush with the cross bar. Each of the two lower corners of the screen 15 is provided with a reinforcing corner plate 20 having a horizontally extending portion 21 which extends across the lower face of the screen frame and is seated within a recess cut in the frame similar to the recess provided in the outer supporting frame for the web 19. A spring tongue 22 integral with the portion 21 is bent backwardly upon said portion, as clearly shown in Fig. 1 of the drawing to lie between said portion and the web 19. As shown in Fig. 3 of the drawing the web 19 is curved to present a convex surface on its upper face and the spring tongue 22 is similarly curved so that the sections of the screen will be held resiliently with the outer frame.

A pivot or hinge pin 23 having an enlarged head 24 is secured by the portion 21 to the screen and projects through the spring tongue 22 and the web 19 into a hole 25 in the outer frame.

Each of the upper corners of the screen 15 is provided with a corner plate 26 similar in construction to the bottom corner plates except that the tongue 27 which is bent backwardly upon itself in the same manner as the spring tongues 22 is not curved transversely. The main function of the bent tongues 27 used at the upper corners of the screen is to provide a double bearing for the upper pivot and hinge pins 28, which it will be noted extend through a tongue 29 formed integral with and extending laterally from an end bracket 30 secured to the upper end of the uprights 11 of the outer supporting frame.

The end brackets 30 are provided with a boss 31 a short distance from the top thereof

in which a thumb screw 32 is mounted. Screw 32 has secured to its outer end the thumb piece 33, to which is pivotally secured the serrated disc 34. Similar thumb screws 32 and discs 34 may be provided at the lower ends of the outer frame. A catch 35 of U or channelled cross sectional configuration is pivotally mounted to one of the sections of the screens and serves to lock the screen sections in closed position.

The operation of the construction shown in Figs. 1 to 5 of the drawing is as follows, the outer supporting frame is placed within the window frame with the screen sections 15 pivotally secured thereto and the entire structure is extended to the full width of the window sash guideway. The catch 35 is now swung to the dotted line inoperative position shown in Fig. 1 and the screen sections 16 and 17 are swung upon their pivotal mounting to their opened positions to permit free access to the thumb screws, which are adjusted to clamp the outer supporting frame securely in position within the sash 20 guideways. It will be noted that the screen sections 16 and 17 may be swung either inwardly or outwardly and that the spring tongues 22 while holding the sections in their closed position, will also permit them 25 to be opened and will bear against the webs 19 with a sufficient pressure to hold the screen sections in opened position, thereby preventing the sections from swinging to the closed position when the screen has been 30 opened to raise an awning or for any other purpose. As no upper cross bar is used in the outer frame it will be noted that a clear unobstructed window opening is secured when the screen sections are moved to 35 opened positions.

In the form shown in Figs. 6 and 7, an upright 40 is provided at only one side, to which upright, the extensible screen 41, composed of the sections 42 and 43, is pivotally secured as by means of the slip hinges 44. The upright 40 is secured within the sash guideway in this form by means of thumbs 45 screws 32 and serrated discs 34.

When it is desired to open the screen the 50 section 43 is slid to the right a sufficient distance to clear the outer guideway strip 45 and thereby allow the screen to be swung outwardly upon the hinges to opened position.

In the form shown in Fig. 8 the construction of the extensible screen is similar to that shown in Figs. 6 and 7, but the upright 40^a is permanently secured to the outer guideway strip 45 as by means of the screws 55 46. A turnbutton 47 is pivotally secured to the side of the screen opposite to the upright 40^a for the purpose of locking the screen in closed position.

In Fig. 9 is illustrated an application of 60 a flexible strip 50 of felt, rubber or other

suitable material to close the gap which would otherwise be present between the top of the screen and the sash. This construction is particularly applicable to the forms shown in Figs. 6 to 8 inclusive but would not usually be required with the construction shown in Figs. 1 to 4.

It will be understood that the various means for securing the screen to the window, such as the screws 32 to 46 are merely 75 illustrative and that any equivalent means may be employed.

Having thus described my invention I declare that what I claim as new and desire to secure by Letters Patent of the United 80 States is,

1. In a window screen, an outer supporting frame comprising a pair of vertical uprights and an extensible cross bar secured to and connecting the lower extremities of said 85 uprights; a screen section pivotally secured to each of said uprights for free movement to opened position, means for detachably securing said supporting frame rigidly within a window frame and means to lock said 90 screen sections in closed position, said supporting frame being free from connecting cross bars at the upper end thereof whereby a free, unobstructed opening will be provided when said screen sections are moved 95 to opened positions.

2. In a window screen, an outer supporting frame, comprising a pair of vertical uprights, and an extensible cross bar secured to and connecting the lower extremities of 100 said uprights; a pair of screen sections, means comprising a spring tongue to pivotally secure said screen sections to said supporting frame, means for rigidly securing said supporting frame detachably to a window frame and means to lock said screen sections in closed position.

3. In a window screen, an outer supporting frame comprising a pair of vertical uprights and an extensible cross bar secured 110 to and connecting the lower extremities of said uprights; a pair of screen sections; said supporting frame and screen sections being provided at their outer corners with reinforcing corner plates, each of said corner 115 plates having a horizontally extending portion extending adjacent and parallel to the horizontally extending portion of the adjacent corner plate, and pivot pins passing through said adjacent parallel horizontal portions to pivotally connect said screen sections to said supporting frame.

4. In a window screen, an outer supporting frame comprising a pair of vertical uprights and an extensible cross bar secured to 125 and connecting the lower extremities of said uprights; a pair of screen sections, said supporting frame and screen sections being provided at their outer corners with reinforcing corner plates, each of said corner plates hav- 130

ing a horizontally extending portion extending adjacent and parallel to the horizontally extending portion of the adjacent corner plate, one of the horizontally extending portions of each pair of lower corner plates being extended and bent backwardly upon itself to form a spring tongue, and a pivot pin passing through each aligned set of said horizontal parallel portions to pivotally connect said screen sections to said supporting frame.

5. In a window screen, an outer supporting frame comprising a pair of vertical uprights and an extensible cross bar secured to and connecting the lower extremities of said uprights; a pair of screen sections, the lower outer corners of said screen sections and supporting frame being provided with reinforcing corner plates, the corner plates 20 of said supporting frame having a horizontally extending portion the upper surface of which is concaved transversely, a spring tongue extending from the corner plate of the screen section, a pivot pin passing through said spring tongue and horizontally extending portion to pivotally connect said screen sections to said supporting frame, and said spring tongue being curved transversely to conform to said concaved upper surface and adapted to press against said upper surface with a yielding pressure whereby the transversely curved surface of said spring tongue will snap into engagement with the curved upper surface

of said horizontally extending portion when 35 said spring tongue is brought into alignment with said portion.

6. In a window screen, an outer supporting frame comprising a pair of vertical uprights and an extensible cross bar connecting 40 the lower extremities of said uprights, means for rigidly securing said supporting frame detachably to a window frame, a pair of screen sections, means to pivotally connect said screen sections to said supporting frame 45 comprising reinforcing corner plates secured to the lower outer corners of said screen sections and supporting frame, and a spring tongue projecting from one of said corner plates and bearing against the adjacent corner plates with a resilient pressure.

7. In a window screen, an extensible screen comprising a pair of screen sections interconnected for relative sliding movement, a supporting member comprising a vertical upright to the side of which one of said screen sections is pivotally secured to permit said screen sections to be swung freely as a unit to opened position, and means for detachably securing said supporting member rigidly within to a window frame, said supporting member being free from horizontal cross bars at the upper end thereof whereby a free unobstructed window opening will be provided when said screen 65 sections are swung to opened position.

EDWARD NUEBLING.
